[57] CLAIM

The ornamental design for a dual terminal electrode for medical monitoring, substantially as shown and described.

DESCRIPTION

FIG. 1 is a perspective view showing the bottom or skin adhering surface of the dual terminal electrode for medical monitoring.

FIG. 2 is a plan view of the skin adhering surface of my electrode design;

FIG. 3 is a plan view of the opposite surface of said electrode from that shown in FIG. 2;

FIG. 4 is a side elevational view of the electrode of FIG. 1;

FIG. 5 is a front elevational view of the electrode as shown in FIG. 1.

FIG. 1

FIG. 2

FIG. 3

FIG. 4
